Attorney

UNITED STATES PATENT OFFICE

WALTER P. KIDD, OF RICHMOND, VIRGINIA

FURNACE COIL

Application filed February 10, 1930. Serial No. 427,339.

This invention appertains to water heaters and more particularly to an improved water coil or loop for heating furnaces. One of the primary objects of my invention is the provision of an improved hot water coil or loop for furnaces which is so constructed that the cold water inlet and the hot water outlet thereof can be adjusted relative to one another to vary the distance therebetween whereby the inlet and outlet pipes can be readily fitted in the openings in the furnace wall provided for that purpose irrespective of the varying distances between said openings.

In the placing of the hot water loop or coil in furnaces considerable difficulty has been experienced by the plumbers and steam fitters in view of the fact that the openings provided in the furnace wall for the inlet and outlet pipes of the loop or coil are spaced apart different distances making it necessary to use various types of coupling joints and sometimes making it necessary to provide another hole in the furnace wall.

It is therefore another salient object of my invention to provide a hot water loop or coil embodying a pair of independent members, one of which carries the cold water inlet pipe and the other the hot water outlet pipe with means whereby the members can be adjustably connected together so that the inlet and outlet pipes can be accurately set according to the space between the openings in the furnace wall.

A further object of my invention is the provision of novel means for forming the members constituting the hot water loop or coil whereby an increased radiating surface will be provided for the coil or loop to insure the proper and quick heating of the water therein and to also prevent the banking of dead ashes and coal thereabout.

A still further object of my invention is to provide an improved hot water loop or coil for furnaces of the above character, which will be durable and efficient in use, one that will be simple and easy to manufacture, and one which can be placed upon the market at a reasonable cost.

With these and other objects in view, the

invention consists in the novel construction, arrangement and formation of parts, as will be hereinafter more specifically described, claimed, and illustrated in the accompanying drawings, in which drawings:—

Figure 1 is a vertical longitudinal section through the improved hot water loop or coil.

Figure 2 is a horizontal section taken on the line 2—2 of Figure 1 illustrating the formation of the upper member of the loop or coil.

Figure 3 is a transverse section taken on the line 3—3 of Figure 1 illustrating the formation of the lower member of the hot water loop or coil.

Referring to the drawings in detail, wherein similar reference characters designate corresponding parts throughout the several views, the letter A generally indicates my improved hot water loop or coil for furnaces, which comprises an upper member 10 and a lower member 20.

The upper member 10 is of substantially an inverted L shape embodying the elongated tubular leg 11 and the short upper horizontal leg 12, having the restricted hot water outlet 13, which can be internally threaded as at 14. This hot water outlet 13 is adapted to be inserted through the opening in the wall of the furnace (not shown) and to have the hot water supply pipe connected therewith. The body portion 15 of the upper member 10 which connects the legs 11 and 12 together is of a greater diameter than the legs so as to prevent the free passage of water therethrough.

This body portion 15 at adjacent parts of the lower and upper legs 12 are provided with struck out ribs 16, which radiate from the outer face of said member.

These ribs 16 serve a triple function, namely first increasing the active area of the members so as to facilitate the heating of the water, second, to increase the strength of the member, and, third, to space the coals from the member. The depending vertically disposed leg 11 below the ribs 16 is provided with external threads 17, for a purpose, which will be later described.

The lower member 20 is of a substantially

- U-shape in side elevation embodying the side legs 21 and 22 and the connecting arcuate body portion 23, the lower end of which may be provided with a drain opening 24. 5 This drain opening receives a suitable movable plug, (not shown) and is provided for the purpose of permitting the cleaning and draining of the coil or loops when desired. As shown, the leg 21 extends above the leg 10 22 and is internally threaded as at 25 for the reception of the threaded portion 17 of the depending leg 11. By this construction and arrangement the lower member 20 can be threaded on the upper member 10 as 15 shown in the drawings. The leg 22 carries the right angularly extending cold water inlet 26 which is arranged in parallel relation to the hot water outlet 13. It is obvious that the lower member 20 can be threaded on the leg 11 until the outlet and inlet members 13 and 26 are spaced the required distance apart after which the inlet and outlet members can be placed in the holes provided for that purpose in the furnace wall. The cold 20 25 water inlet 26 is internally threaded for the reception of the cold water supply pipe (not shown).

A packing nut 27 can be provided for preventing leakage between the two members 30 and for holding the members in their proper adjusted position and this packing nut 27 is threaded on the depending leg 11 and on the upper end of the leg 21 of the lower member 20. Suitable packing material 28 35 is placed between the nut 27 and the upper edge of the leg 21 of said lower member.

The lower member 20 can be provided with radially extending struck out hollow ribs 29 which serve the same purpose as the 40 ribs 16, namely to increase the radiating surface of the coil or loops, to strengthen the member 20 and to space the coals and ashes from loops.

From the foregoing description, it can be 45 seen that I have provided a novel heating coil or loop in which the two members carrying respectively cold water outlet and the hot water inlet can be readily adjusted relative to one another so as to span the distance between the apertures provided for said inlet and outlet in the wall of the furnace.

Changes in detail may be made without departing from the spirit or scope of the invention, but

55 What I claim as new is:

1. A hot water loop for heating furnaces comprising an inverted L-shaped member having a depending externally threaded leg at one side and a hot water outlet at its other side, a lower member including a U-shaped body having an internally threaded leg at one side and a right angularly extending cold water inlet at its opposite side, the lower member receiving the depending externally 60 threaded leg and adjustable thereon, and a

packing nut threaded on the externally threaded leg and said internally threaded leg.

2. A hot water loop for heating furnaces comprising an inverted L-shaped member 70 having a depending externally threaded leg at one side and a hot water outlet at its other side, a lower member including a U-shaped body having an internally threaded leg at one side and a right angularly extending cold 75 water inlet at its opposite side, the lower member receiving the depending externally threaded leg and adjustable thereon, a packing nut threaded on the externally threaded leg and said internally threaded leg, and radially extending hollow ribs formed on the outer surface of the upper and lower member and communicating with the interior thereof.

3. A hot water loop for heating furnaces comprising a body having a cold water inlet 85 and a hot water outlet, and comparatively shallow flutes formed on said body communicating with the interior thereof and projecting beyond said body for facilitating the heating of the water in the body and to space 90 the coals and ashes from the outer face of said body, said flutes being located in the direct path of the water passing through the body to permit of a continuous flushing of the flutes and prevent the accumulation of 95 sediment therein.

4. A hot water loop for heating furnaces comprising a body having a cold water inlet and a hot water outlet, and radially extending 100 comparatively shallow hollow ribs constituting flutes formed on the outer face of the body and communicating with the interior thereof, said flutes being located in a position to cause the flutes to be flushed as the water enters and leaves said body. 105

5. A hot water loop for heating furnaces comprising an inverted L-shaped member carrying a depending externally threaded leg at one side and a hot water outlet at the other side, a lower member including a 110 substantially U-shaped body having an internally threaded leg at one side and a right angularly extending cold water inlet at its opposite side, and means for adjustably and removably connecting said first mentioned 115 member and the lower member together.

In testimony whereof I affix my signature.

WALTER P. KIDD.
